UNITED STATES PATENT OFFICE

115,946

DESIGN FOR A BAFFLE PLATE FOR OIL BURNING STOVES

Clarence F. Wiley, Norton, Mass., assignor to
Glenwood Range Company, Taunton, Mass.,
a corporation of Massachusetts

Application April 28, 1939, Serial No. 84,651

Term of patent 3½ years

To all whom it may concern:

Be it known that I, Clarence F. Wiley, a citizen of the United States and resident of Norton, in the county of Bristol, State of Massachusetts, have invented a new, original, and ornamental Design for a Baffle Plate for Oil Burning Stoves, of which the following is a specification, reference being had to the accompanying drawing, forming part thereof.

Fig. 1 is a top plan view of the baffle plate for oil burning stoves, showing my new design;

Fig. 2 is a view in side elevation thereof; and

Fig. 3 is a perspective view thereof partly broken for convenience of illustration.

I claim:

The ornamental design for a baffle plate for oil burning stoves, substantially as shown.

CLARENCE F. WILEY.
